(57) **CLAIM**

The ornamental design for a pet carrier as shown and described.

DESCRIPTION

FIG. 1 is a front perspective view showing our new design; FIG. 2 is a front view thereof; FIG. 3 is a top plan view thereof; FIG. 4 is a left side view thereof; FIG. 5 is a right side view thereof; FIG. 6 is a rear view thereof; FIG. 7 is a rear perspective view thereof; and, FIG. 8 is a bottom view thereof.

The broken lines depict portions of the pet carrier that form no part of the claimed design.

1 Claim, 8 Drawing Sheets
